APPARATUS FOR WEAVING PILE FABRICS

John Jacob Kauffmann, Elkins Park, Pa., assignor
to Steel Heddle Manufacturing Company,
Philadelphia, Pa., a corporation of Pennsylvania

Application September 1, 1933, Serial No. 687,776

7 Claims. (Cl. 139—37)

My invention relates to apparatus for weaving pile fabrics, and it relates particularly to that type of apparatus in which pile forming wires or gauges, extending parallel to the warp, are used for holding the pile loops above the ground cloth while the fabric is being formed.

My invention, while applicable for use in connection with various styles of pile forming wires, is particularly useful in the weaving of fabrics such as friezes and the like, in which the pile is relatively low, and in the weaving of which the pile forming wires are shedded so that the shuttle may pass above or below the same, as may be required by the structure of the weave.

Originally, in the weaving of low pile fabrics such as friezes and the like, a false warp was used, comprising a series of cords secured at the rear of the loom. As the cloth is fed forwardly in the weaving, these cords are withdrawn from the fabric. The principal objections to the use of the cords are the constant wearing, and the fact that often pieces break off the ends of the cords and remain in the finished fabric.

In the development of the art, wires have been substituted for the cords. When round wires are used, they necessarily have to be of sufficient diameter to raise the pile the required amount, and consequently they crowd the splits in the reed, often causing breakage of the warp as the same is shedded past the wires, by reason of the incompressible nature of the wires as compared with the cords.

When flat wires are used, the same will twist when shedded, due to the natural tendency of such wires to turn on their flat sides when bent. This twisting also causes crowding of the splits of the reed, and interferes with the proper shedding of the warp past the wires. The twisting of the flat wires also results in considerable wear on the reed dents, thereby greatly shortening the life of the reed.

The tendency of the pile forming wires to twist is also present to some extent in the relatively wider stationary styles of pile forming wires, such as are used in double shuttle looms where one shuttle passes beneath the pile wires to form the ground cloth, and the other shuttle passes above the pile wires to insert the weft which is used to support the pile loops.

The principal object, therefore, of my present invention is to provide simple and effective means for preventing twisting of flat pile wires, and thereby obviate crowding of the splits of the reed, thus insuring greater freedom of the warp in its passage past the pile wires when the shedding

takes place, and also decreasing the wear on the reed dents.

A further object of my invention is to provide improved apparatus which is particularly adaptable for weaving low pile fabrics and the like, and in the use of which a more evenly woven fabric is obtained.

A further object of my invention is to provide apparatus of the character aforesaid, for weaving pile fabrics, in the use of which breakage of the warp, by reason of crowding in the reed, will be reduced to a minimum.

With the foregoing objects in view, my invention contemplates the provision in a specific embodiment thereof, of an improved form of apparatus for weaving low pile fabrics in which a flat pile wire is employed, which may be raised and lowered to desired positions to permit the shuttle to pass below and above the same, as required in the formation of the weave, and which is so constructed and arranged as to minimize crowding of the warp in the reed splits as the same pass the pile wires in the formation of the successive sheds.

The nature and characteristic features of my invention will be more readily understood from the following description, taken in connection with the accompanying drawing forming part hereof, in which:

Figure 1 is a diagrammatic view illustrating one form or embodiment of my invention, as used for the weaving of a low pile fabric of a typical formation, in the weaving of which the pile wire gauges are shedded so that the weft shots may be inserted above or below the pile wires as required;

Fig. 2 is a fragmentary perspective view of a portion of a pile wire of the type shown in Fig. 1, and a portion of a heddle of novel form in operative relationship therewith.

Fig. 3 is a side elevation of the portion of the apparatus shown in Fig. 2;

Fig. 4 is a front elevation of the portion of the apparatus shown in Fig. 3, the pile wire being shown in section;

Fig. 5 is a fragmentary elevation of a portion of the reed, the pile wires and warp ends being shown in section, and in operative relationship therewith;

Fig. 6 is a horizontal section of a portion of the reed, with portions of the pile wires shown in operative relationship therewith; and

Fig. 7 is a view similar to Fig. 2, showing the arrangement employed in connection with rel-

atively wider pile wires such as are used, for example, in double shuttle looms.

Referring to the drawing, in Fig. 1 thereof there is shown, more or less diagrammatically, a set-up for weaving a pile fabric of simple type. As there shown, 10 and 11 are the ground warps, and 12 is the pile forming warp. 13 are the ground wefts, and 14 are the pile loop supporting wefts, which in some instances are left in the fabric, and in other instances are pulled out after the fabric is woven.

The ground warp ends 10 and 11 are shedded in the usual manner by the heddles 15 and 16, respectively, and the pile forming warp ends are likewise shedded by the heddles 17.

The pile forming wires 18 are secured at their rear ends by means of eyes 19, through which a transverse rod 20 extends. The rod 20 is in turn secured to a transverse bar 21 at the rear thereof.

The pile wires 18 extend through the reed 22, between the dents 23 thereof, into the fell of the cloth, pile loops being formed by the insertion of the weft shots 14 over the top of the pile wires. The pile wires 18 are flattened, the thickness thereof being appreciably less than the width of the reed splits (see Figs. 5 and 6).

The pile wires 18 are raised for the insertion of the weft shots 13 in the ground cloth, and lowered for the insertion of the weft shots 14 which support the pile loops, this raising and lowering of the pile wires being accomplished by means of heddles 24 interposed between the warp shedding heddles and the reed 22. It will be appreciated that, by reason of the bending of the pile wires 18 intermediate their ends, when the same are raised and lowered there will be a pronounced tendency of said wires to twist about their longitudinal axes.

To prevent the twisting above mentioned, the heddle 24 is provided with an eye 25 of peculiar formation, as shown in Figs. 2, 3, and 4 of the drawing. This eye 25 as there shown is formed by slitting the metal of the heddle 24 in a direction parallel to its length, then offsetting the slitted portions out of the main plane of the heddle, the central portion 26 being offset in one direction, and the two side portions 27 being offset in the other direction. The offset is merely of such extent as to engage the flat sides of the pile wire 18 where said wire extends through the eye 25. Hence the offset portions will effectively serve to prevent twisting of the wire 18.

In Fig. 7 of the drawing, there is shown the application of a heddle of the same type to a pile wire 28 of the style which is used in connection with double shuttle looms, in which the pile wires are stationary, and one shuttle passes below the pile wire and one shuttle passes above the pile wire. In this instance, the formation of the heddle 24 is substantially the same as that of the heddle shown in Figs. 2, 3, and 4, the offset portions 26 and 27 being merely elongated sufficiently to take care of the extra width of the pile wire 28 there shown.

It will, of course, be understood that the arrangement shown is for weaving a simple form of pile fabric, and that for weaving fabrics of a more complex type, the arrangement will be modified accordingly.

It will also be seen that the invention is equally applicable for weaving fabrics in which the pile is formed by traversing the pile warp back and forth over the pile wire, by means of doup harness or equivalent mechanism.

I claim:

1. Apparatus for weaving pile fabrics comprising the combination in a loom of flat wires which are raised and lowered as required in the formation of the weave and by means of which the pile loops of the fabric are formed, said wires extending through the warp shedding harness and through the reed parallel to the warp, and means interposed between the warp shedding harness and the reed of the loom engaging the side faces of the wires thereby to prevent twisting of said wires. 10

2. Apparatus for weaving pile fabrics comprising the combination in a loom of flat wires which are raised and lowered as required in the formation of the weave and by means of which the pile loops of the fabric are formed, said wires extending through the warp shedding harness and through the reed parallel to the warp, and heddles each having an eye through which a pile wire extends, the eye portion of each heddle having parts engaging the side faces of the pile wire thereby to prevent twisting of said wire. 15

3. Apparatus for weaving pile fabrics comprising the combination in a loom of flat wires which are raised and lowered as required in the formation of the weave and by means of which the pile loops of the fabric are formed, said wires extending through the warp shedding harness and through the reed parallel to the warp, and heddles each having an eye through which a pile wire extends, each of said eyes being formed by slitted portions which extend out of the main plane of the heddle and engage the side faces of the pile wire thereby to prevent twisting of said wire. 20

4. Apparatus for weaving pile fabrics comprising the combination in a loom of flat wires which are raised and lowered as required in the formation of the weave and by means of which the pile loops of the fabric are formed, said wires extending through the warp shedding harness and through the reed parallel to the warp, and heddles interposed between the warp shedding harness and the reed, each of said heddles having an eye through which a pile wire extends, each of said eyes being formed by slitted portions which extend out of the main plane of the heddle and engage the side faces of the pile wire thereby to prevent twisting of said wire. 25

5. Apparatus for weaving pile fabrics comprising the combination in a loom of flat wires which are raised and lowered to permit the insertion of weft shots above and below the wires as required in the weave and by means of which the pile loops of the fabric are formed, and heddles for raising and lowering said pile wires, said heddles being made of thin flat metal and having eyes through which said pile wires extend, each of said eyes being formed by slitted portions which extend out of the main plane of the heddle and engage the side faces of the wire, said heddles being positioned between the warp shedding harness and the reed of the loom. 30

6. Apparatus for weaving pile fabrics comprising the combination in a loom of flexible pile forming wires extending parallel to the warp and having flat side faces, and means for flexing said wires intermediate their ends comprising heddles each having an eye portion through which a pile wire extends, each of said eye portions having parts engaging the flat side faces of said wire for preventing twisting of said wire. 35

7. Apparatus for weaving pile fabrics comprising the combination in a loom of pile forming wires extending parallel to the warp and having flat side faces, a member disposed to the rear of the warp shedding harness to which the rear ends of said pile wires are secured, and means for preventing twisting of said wires com-

prising heddles each having an eye portion through which an intermediate portion of a pile wire extends, the eye portion of each of said heddles having parts engaging the flat side faces of the wire passing therethrough.

5
